UNITED STATES PATENT OFFICE.

PERLEY R. GLASS, OF BROOKLINE, MASSACHUSETTS, ASSIGNEE, BY MESNE ASSIGNMENTS, TO UNITED SHOE MACHINERY CORPORATION, OF PATERSON, NEW JERSEY, A CORPORATION OF NEW JERSEY.

FASTENER-SETTING MACHINE.

1,334,238.

Specification of Letters Patent. Patented Mar. 16, 1920.

Application filed May 19, 1917. Serial No. 169,761.

To all whom it may concern:

Be it known that I, PERLEY R. GLASS, a citizen of the United States residing at Brookline, in the county of Norfolk and State of Massachusetts, have invented certain Improvements in Fastener-Setting Machines, of which the following description, in connection with the accompanying drawings, is a specification, like reference characters on the drawings indicating like parts in the several figures.

This invention relates to improvements in machines for setting fasteners in sheet material and more particularly to machines for inserting such fasteners as eyelets, hooks or the like in the uppers of boots and shoes.

In setting eyelets in uppers of boots and shoes of certain types considerable difficulty has been experienced by reason of the fact that, as presented to the eyeleting machine, the right or fair side of the upper faces downwardly so that the operator cannot readily locate the point of insertion with the desired accuracy. This difficulty is especially apparent when eyelets are to be set in uppers provided with so-called "military stays". Such stays consist of narrow strips of leather which are either simply ornamental or are secured to cloth or leather uppers of shoes to reinforce the row of eyelets. It is important to insert the eyelets centrally into the military stay because an eyelet that is closer to one side of the stay than to the other detracts from the ornamental appearance of the shoe, and there is also danger that the hole punched for such eyelet will cut one of the seams uniting the stay with the upper and cause the seam to unravel quickly under the lacing strain.

As a rule military stays are not parallel to the lacing edges of the upper. One reason for attaching these stays in a relation other than one parallel to the lacing edge of the uppers is to improve the appearance of the shoe—as, for example, by arranging the two series of eyelets in diverging relation. Another reason is that it requires operators of more than usual skill to attach the stays exactly in parallel relation to the lacing edges of uppers. In eyeleting uppers provided with military stays it is therefore impracticable to employ the usual edge gage of eyeleting machines to indicate the location of the setting points. Hitherto it has

been customary in eyeleting uppers provided with military stays to perform two distinct operations in the first of which the upper, with the right or fair side uppermost, is presented to a punching machine, whereas in the second operation the upper is presented in inverted position to an eyeleting machine, the previously punched holes serving to indicate the location of the points at which the eyelets should be inserted. The general object of the present invention is to provide a single machine by the use of which these and similar disadvantages may be obviated so that accurate location of the eyelets in the work will be insured.

With these conditions in view an important feature of the present invention consists in a gaging device of relatively small dimensions constructed and arranged to indicate by its position upon the upper surface of the work the precise point at which the eyelet hole will be punched and the eyelet inserted when the machine is set in operation. As herein shown the punch is disposed beneath the work support so as to punch upwardly and the anvil against which the punch acts is disposed above the work and has also the function of such a gaging device. Accordingly, in using the machine of my invention, the work may be presented right side up and the anvil will cover merely the eyelet receiving area of the work while permitting a clear view of the surrounding work. Consequently, in dealing with an upper having military stays the operator has only to position the work so that the anvil will cover the desired eyelet-receiving area of the stay to insure the correct location of the eyelet.

Another feature of the invention consists in an anvil or other gaging device so combined with work-feeding mechanism of the machine that its initial position will be determined in accordance with the length of the steps of the feeding mechanism. In the machine herein shown the anvil is connected to a feed-regulating lever so that its position will be controlled by the movement of the lever, and the anvil consequently indicates not only the position at which the first eyelet is to be inserted but also, by its distance from the eyelet inserting die, the length of the feeding step to be imparted to

the work. This arrangement is advantageous in that it relieves the operator from the necessity of making a separate adjustment of the gage or anvil.

5 This and other features of the invention including certain details of construction and combinations of parts will be described in connection with an illustrative machine shown in the accompanying drawings, in 10 which,—

Figure 1 is a view of the machine in side elevation with parts of the frame broken away;

15 Fig. 2 is a view in perspective of the mechanism for operating the punch and anvil;

Fig. 3 is a detail of the upper setting device;

20 Fig. 4 is a fragmentary view in perspective of the raceway operating mechanism;

Fig. 5 is a front view of the machine;

25 Figs. 6, 7 and 8 show diagrammatically the relative positions of the operative parts of the machine, before and after the punching operation and at the completion of the setting operation.

Fig. 9 is a fragmentary view of an upper provided with a military stay.

30 The machine frame 2 is provided with bearings for the main shaft 4, carrying on one end a driving pulley 6. A clutch mechanism of well known type is interposed between the pulley 6 and the main shaft 4, and the starting and stopping of the 35 machine is controlled through this mechanism.

40 A combined punching and setting tool 8 is mounted below the work table 9 in a head 10, to which vertical reciprocations are imparted by toggle links 12, 14. The latter 45 of these links is pivoted upon a rod 30 mounted in the frame of the machine while the link 12 is slidably pivoted on a rod 13 held in forked arms on the lower end of the head 10. A link 18 connects the knuckle joint 16 of the toggle 12, 14 with the extended arm 22 of a cam lever 20 pivoted to the machine frame 2 at 24. The forked end of the cam lever 20 surrounds a cam 26 mounted on the main shaft 4. The cam 50 26 is arranged to move the toggle links 12, 14 slightly beyond the straightened position in order to relieve the pressure of the punch upon the work after the punching operation. The head 10 is mounted for movement within a casing 28 which is arranged to slide laterally upon a pair of stationary rods 30, 32 in feeding the work.

55 The punch 8 is elevated from beneath the work and acts against an anvil 34 secured to the lower end of an anvil bar 36. The anvil bar 36 is normally fixed in position but is mounted in a casing 38 which may be adjusted laterally on two stationary rods 41, 42. The face of the anvil 34 is located 60 approximately in contact with the upper

surface or right side of the work and indicates exactly the point where the eyelet is to be set. The dimensions of the anvil approximate those of an eyelet for a considerable part of its vertical extent and hence 70 are such that it does not obstruct the view of the work around the setting point thus giving the operator opportunity to locate the setting point with the greatest exactness. An adjustable forked foot 40 is secured to the lower end of the anvil bar 36 to hold the work on the end of the punch 8 during the feeding movement, but the foot 40 does not interfere with the visibility 75 of the work around the setting point. 80

The feeding movement of the punch 8 is derived from a slide 43 which is reciprocated horizontally by a cam 44 (Fig. 4) mounted on the main shaft 4. The cam 44 acts through links 46, 48 upon an arm 50 85 secured to the upper end of a shaft 52. The lower end of the shaft 52 is connected with a forked arm 54 which engages at its forward end with a block 57 on the casing 28 of the head 10. The length of the feeding 90 movement of the punch 8 can be varied by the manipulation of a spacing lever 56 which shifts the point of connection of the links 46, 48 through a link 58 and which may be suitably held at the desired point. 95 A treadle connection 57 is provided which may be used for moving the spacing lever if desired. The initial or stop position of the punch will be determined by the setting of the spacing lever 56 but its final 100 position after feeding the work is invariable and always in alinement with the top set.

105 The anvil 34 may be elevated to permit the ready insertion of the work by the following mechanism: The upper end of the anvil bar 36 is slidably connected with a rod 63 extending between the arms of the link 62 of a pair of toggle links 60, 62. A link 64 connects the knuckle joint of the 110 toggle 60, 62 with an arm 65 secured to a shaft 66, to which a treadle arm 68 is fastened. A spring 70 acting upon the treadle arm 68 tends to hold said arm against an adjustable stop 71 so that the toggle links 115 60, 62 are maintained slightly beyond their straightened position, thus rigidly supporting the anvil in a position immediately adjacent and preferably almost touching the work. Upon depression of a treadle rod 120 72 connected with the arm 68 the toggle 60, 62 is broken and the anvil elevated. The casing 38 carrying the anvil bar 36 is adjusted laterally on the rods 41, 42, movement of the anvil bar 36 being permitted 125 by reason of its sliding connection to the pin 63, by a lever 74 pivoted in the frame and having at its outer end a roller 76 which runs in a cam track 78 in the spacing lever 56. When the spacing lever 56 130

is set to determine the length of the individual feeding movements, the anvil 34 is adjusted into proper initial position but after having been thus adjusted has no movement during the regular operation of the machine. This setting of the spacing lever will also adjust the stop position of the punch 8 to correspond with the adjusted position of the anvil 34, as previously described.

The upper setting tool 80 is secured to the lower end of a bar 82 which is guided in the frame for vertical movement but has no lateral movement. Vertical movements are imparted to the bar 82 and the upper setting tool 80 by a crank lever 84 pivoted at 88 to the machine frame. Movements of the crank lever 84 are derived from the main shaft by means of a curved slot and block connection 90, 92, said block being actuated by a crank on the main shaft 4.

Eyelets are supplied to the upper setting tool by a raceway 94 which is pivoted to the frame at 95 and is oscillated by connections with the slide 43 (see Fig. 4). The slide 43 is provided with a projection 96 carrying a block 98. The block 98 is received between the arms of a forked lever 100 secured to the lower end of a vertical shaft 102. The upper end of the shaft 102 carries a yoke piece 104, between the arms of which is pivoted a second yoke piece 106. The yoke piece 106 is provided with an arm 108 having an adjustable stop screw which is normally held against the hub of the yoke piece 104 by a spring 110. Between the arms of the inner yoke 106 is disposed a block 112 having vertical pins 114 arranged to slide freely through the arms of the yoke piece 106. A pin 116 extends horizontally from the block 112 through bosses 118 on the raceway 94. All these parts act normally as a single piece, allowing the necessary lost motion. When it is desired to hold the raceway in inoperative position, the arm 108 of the inner yoke 106 is swung in opposition to the tension of the spring 110, and the raceway thus shifted out of the range of the upper setting tool. Adjustment of the eyelet delivering position of the raceway is effected by means of the screw in said arm 108. A belt connection 130 provides for the actuation of the usual agitator mechanism.

The described arrangement of the raceway offers particular advantages. The operator can actually see the lowermost eyelet in the raceway as it is picked out by the upper set and can stop the operation of the machine in time in case the raceway should fail for any reason to deliver an eyelet.

The upper setting device is vertically adjustable to adapt the machine to operate upon stock of varying thickness. The bar 82 carrying the upper setting device 80 is

provided with a block 120 (see Fig. 3) which is received between the arms of a fork 122 of the crank lever 84. After loosening a binding screw 124 in the fork 122 the relative position of the latter may be adjusted by turning the screw 126 to lower or elevate the bar 82 and the upper setting device 80 in accordance with a given thickness of stock.

The initial positions of the operative parts of the machine are illustrated in Fig. 6. The anvil 34 rests in a normally fixed position immediately adjacent to the upper surface or right side of the work which has been previously positioned under the anvil. The initial position of the anvil, as determined by the manipulation of the spacing lever 56 in adjusting the length of the individual feeding movements, accurately indicates the point in the work at which the eyelet will be set. The forked foot 40, holding the work during the feeding movement upon the punch 8, is so shaped that it does not obstruct the full view of the work around the setting point. The anvil thus forms a gage, which may be positioned over a stay 140 previously attached to an upper 141 to indicate the location of the setting point of eyelets 142 (see Fig. 9); and since there are no other parts of the machine in close proximity to the setting point, the operator is enabled to position the work accurately with ease and without loss of time. The diameter of the anvil is preferably somewhat less than the diameter of the eyelet flange so that the operator is enabled to correct any inaccuracy of the location of the setting point before the punching and setting operation. Fig. 7 shows the positions which the parts occupy after the punch has perforated the work. The punchings will accumulate within the bore (see Fig. 8) in the interior of the punch and gradually drop into a suitable receptacle placed beneath the lower end of the punch. This is of particular advantage since it relieves the operator from the necessity of removing the accumulated punchings, as must be done in machines where the punch descends during its operative stroke. During the punching operation the upper setting tool has been lowered into the lowermost eyelet in the raceway and the latter has been swung out of range of the upper setting tool, the tapering spindle of the upper setting tool acting to hold the eyelet frictionally as shown in Fig. 7.

After the completion of the punching operation the pressure exerted by the punch upon the work and the anvil is relieved by moving the toggle 12, 14 slightly past center. The punching and setting tool 8 is then moved laterally with the work to a position beneath the upper setting tool, so that the tool may perform its upsetting function during the insertion of the eyelet. The

upper setting tool 82 is now lowered, the barrel of the eyelet inserted through the work and upset by the coöperation of the upper setting tool and the tool 8 as shown in Fig. 8. At the completion of the setting operation the parts of the machine are returned to their initial positions as shown in Fig. 6 ready to repeat the cycle of operations.

10 Having described my invention, what I claim as new and desire to secure by Letters Patent of the United States is:

1. In a machine of the class described, 15 punching and eyelet setting dies and a gag-
ing device having a terminal of the magni-
tude of an eyelet extending down closely
adjacent to the work, said terminal being
constructed and arranged to indicate by its
position upon the upper surface of the work
20 the point in the work at which the eyelet
will be set by said dies.

2. In a machine of the class described, 25 punching-and-setting mechanism comprising a punching-and-setting tool arranged to
operate against the under side of the work,
and a device formed and arranged to indicate
on the upper side of the work the point
at which the hole will be punched, said de-
vice being operable conjointly with said tool
30 to punch the hole, said mechanism being
constructed and arranged to permit move-
ment of the work relatively to said device
prior to being punched but while the latter
is in contiguous relation to the work, to rec-
35 tify inaccuracy of position.

3. In a machine of the class described, 40 punching - feeding - and - setting mechanism comprising an upper setting device, an anvil formed and arranged to indicate on the up-
per side of the work, an operating point
upon the work, and a punch beneath the
work constructed and arranged to punch the
work conjointly with the anvil and to feed
45 the work from the anvil to the upper set-
ting device.

4. In a machine of the class described, an 50 upper setting device, an anvil arranged above the work, and a punch beneath the work constructed and arranged to act both as a lower setting device and as a means to feed the work.

5. In a machine of the class described, an 55 upper setting device, a normally stationary anvil arranged above the work, a combined punching and lower setting device beneath the work, and means to actuate the combined punching and lower setting device to punch and to feed the work.

6. In a machine of the class described, an 60 upper setting device, a punch beneath the work, an anvil disposed above the work and arranged to co-act with said punch, the di-
ameter of said anvil being less than the width of the flange of an eyelet, and means

laterally disposed with relation to the axis 65 of said anvil for supporting the same.

7. In a machine of the class described, an upper setting device, a combined punching and lower setting device, means to cause the latter to feed the work, and an anvil above 70 the punch constituting a gage indicating directly the setting point on the upper surface of the work.

8. In a machine of the class described, a 75 setting device arranged to operate against the upper side of the work, a member formed and arranged to indicate on the upper side of the work the location at which a hole is to be punched, and a tool formed and ar-
ranged to coöperate first with said indicat- 80 ing member to punch a hole, and subse-
quently to coöperate with said setting de-
vice to set an eyelet in the punched hole.

9. In a machine of the class described, 85 an upper setting device, a punch movable upwardly for perforating and transversely for feeding the work, an anvil above the work, and means for relieving the pressure of the punch upon the anvil after the punching operation and prior to the feed 90

10. In a machine of the class described, an upper setting device, a combined punching and lower setting device beneath the work, means for feeding the work, an anvil above the work arranged to co-act with said com- 95 bined device and to form a gage to locate the setting point, and means for relieving the pressure of the punch upon the anvil after the punching operation.

11. In a machine of the class described, an 100 anvil above the work, a punch, means to elevate the punch to press the work against the anvil, and means to move the punch lat-
erally, the punch being movable to relieve the pressure upon the anvil prior to the 105 lateral movement.

12. In a machine of the class described, 110 punching-and-setting mechanism comprising a punching-and-setting tool arranged to operate against the lower side of the work, a member arranged to co-act with said tool to punch the work, said member being formed and arranged to indicate on the upper surface of the work, prior to punching, whether the work is in the desired location 115 for punching, so that the position of the work may be corrected if incorrect, a setting mem-
ber arranged to co-act with said tool to set an eyelet in the punched hole, and means for raising said indicating member to facilitate 120 insertion of the work.

13. In a machine of the class described, an upper setting device, an anvil above the work, a punch beneath the work, means for moving the punch laterally to feed the work, 125 toggle mechanism to elevate the punch, and means for moving the toggle beyond its straightened position to relieve the pressure

- of the punch upon the anvil prior to the feeding operation.
14. In a machine of the class described, an upper setting device, a raceway, an anvil above the work, a punch acting as the lower setting device, and means for lowering the upper setting device to receive the lowermost eyelet in the raceway and to set the eyelet in coöperation with the punch. 65
15. In a machine of the class described, an upper setting device, an anvil above the work, a combined punching and lower setting device, a raceway above the work presenting the lowermost eyelet to the upper setting device, and means to move the combined punching and lower setting device and the work laterally. 70
16. In a machine of the class described, an upper setting device, a combined punch and lower setting device, an anvil above the work constituting a gage to indicate the location of the setting point, and means to adjust the anvil to vary the location of said point. 75
17. In a machine of the class described, an upper setting device, a combined punching and lower setting device, means to cause the latter to feed the work, a raceway presenting an upright eyelet above the work, and an anvil above the work. 80
18. In a machine of the class described, a setting device constructed and arranged to feed the work, a combined punch and setting device, an anvil coöoperating with said punch, and means for varying the length of feeding movements and for determining the initial position of the anvil. 85
19. In a machine of the class described, an upper setting device, a combined punch and lower setting device constructed and arranged to feed the work, an anvil disposed above the work and arranged to coöperate with said punch and means to adjust the length of feeding movements, said means serving also to determine the initial position of the anvil in accordance with the desired spacing. 90
20. In a machine of the class described, an upper setting device, a combined punch and lower setting device constructed and arranged to feed the work, an anvil arranged to coöperate with said device, a spacing lever to vary the length of the feeding movements, and a curved slot and link connection between the spacing lever and the anvil to shift the anvil laterally upon adjustment of the spacing lever. 95
21. In a machine of the class described, a punch disposed below the work arranged and constructed to feed the work, a coöperating anvil above the work, means to elevate the anvil to permit insertion of the work, and means to adjust the anvil laterally upon variation of the length of feeding move- 100
- ments without disturbing the operative relation of the anvil to its elevating means. 105
22. A machine of the class described, having, in combination, eyelet setting dies and a gaging device constructed and arranged to indicate by its position upon the upper surface of the work the point at which the eyelet is to be set by said dies, and adjustable means for controlling the position of the gaging device in a plane substantially parallel to the plane of the work. 110
23. In a machine of the class described, eyelet setting and adjustable work feeding means, a gaging device, and means for determining the position of the gaging device in accordance with the adjustment of the work feeding means. 115
24. A machine of the class described, having, in combination, means for supporting the work in a substantially horizontal position, a punch disposed beneath the work and movable toward and from the under side of the work, and an eyelet presenting die arranged above the work supporting means for inserting an eyelet in the hole formed by the punch. 120
25. In a machine of the class described, an anvil arranged in a relatively stationary position above the work, a punch disposed below the work constructed and arranged to punch the work against said anvil to feed the work, and a spacing lever constructed and arranged to vary the length of the feeding movements and connected to said anvil to adjust the lateral position of the anvil upon adjustment of the spacing lever. 125
26. In a machine of the class described, a vertically movable eyelet inserting set arranged above the work, a punch disposed below the work, a coöperating anvil disposed above the work and adjustably fixed in position in accordance with the predetermined length of feeding movement, said punch being constructed and arranged to move the work from the position indicated by the anvil to a position in alinement with the inserting die whereby the relative lateral position of the inserting die and the anvil instantly indicates the length of feeding movement which will be imparted to the work. 130
27. In a machine of the class described, a work support, a punch arranged beneath said work support, a coöperating anvil disposed above the work support, and means to elevate the anvil to facilitate the insertion of work comprising a toggle mechanism constructed and arranged normally to rest in a position slightly beyond the straightened position thereof in order to support said anvil rigidly in its operative position. 135
28. In a machine of the class described, eyelet setting mechanism, a part of which is constructed and arranged to feed the

work, a movable raceway for supplying eyelets to said mechanism, and a main shaft connected to said mechanism for actuating the same, said connections including a sliding member operatively connected both to the feeding mechanism and the raceway actuating mechanism.

29. In a machine of the class described, eyelet inserting mechanism comprising a reciprocating die and a lever connected thereto for actuating said die constructed and arranged in two parts, and means for adjusting the relative positions of the parts of said lever, thereby to adjust the position of 15 the eyelet set.

30. In a machine of the class described, means for setting eyelets in a piece of work comprising an upper setting die arranged above the work and a combined punching 20 and lower setting device arranged beneath the work, and means for feeding the work to insure the setting of the eyelets at regular intervals comprising means for moving the combined punching and lower setting device 25 laterally while in engagement with the work.

31. In a machine of the class described, means for setting eyelets right side up in a piece of work comprising a raceway having its terminal arranged above the level of 30 the work, an upper setting device arranged above the work and a punch acting as a lower setting device and arranged beneath the work, and means for lowering the upper 35 setting device to thread the lowermost eyelet in the raceway and set said eyelet in coöperation with the punch.

32. In a machine of the class described, means constructed and arranged to set 40 an eyelet with its previously constructed flange disposed upon the upper and finished side of the work in view of the operator, said means comprising an upper setting device arranged to present an eyelet in up- 45 right position above the work, a raceway for delivering eyelets thereto and a lower setting device arranged below the work to coöperate with the upper setting device, and means to cause said lower setting de- 50 vice to feed the work laterally to insure the even spacing of the eyelets.

33. In a machine of the class described, mechanism comprising three tools two of 55 which are arranged to coact to punch a hole in the work, one of which is operative to feed the work, and two of which are operative conjointly to set an eyelet in the punched hole, one of the punching tools being formed and arranged to indicate on the 60 work, prior to punching, whether the work is in the desired position for punching, said mechanism being constructed and arranged to permit movement of the work to correct inaccuracy of position prior to punching but

while said indicating tool is in contiguous 65 relation to the work.

34. In a machine of the class described, two coöoperative punching members one of which is arranged to remain stationary within view of the operator and to engage 70 the upper surface of the work, the other one of said members being movable to punch the work conjointly with said stationary member and to feed the work from punching position to eyelet-receiving position, and a 75 setting device arranged to coöperate with said punching-and-feeding members to set an eyelet in the punched hole.

35. In a machine of the class described, means for punching and feeding the work 80 comprising two coöoperative punching members one of which is movable to feed the work, said members being movable toward and from each other, and toggles for moving said members toward and from each 85 other.

36. In a machine of the class described, means for punching and feeding the work comprising two coöoperative punching members one of which is movable to feed the 90 work, said members being movable toward and from each other, automatic toggle mechanism for moving one of said members toward and from the other, and manually operative toggle mechanism for moving the 95 other punching member.

37. In a machine of the class described, means for punching and feeding the work comprising two coöoperative punching members one of which is movable to feed the 100 work, said members being movable toward and from each other, automatic toggle mechanism for moving said punching-and-feeding member toward and from the other punching member, and spring-stressed 105 toggle mechanism for holding the latter said punching member in punching position.

38. In a machine of the class described, means for punching and feeding the work 110 comprising two coöoperative punching members one of which is movable to feed the work, said members being movable toward and from each other, and two independent toggle mechanisms for moving said punching members respectively toward and from each other, the knuckles of said toggle mechanisms being movable across their respective dead center positions.

39. In a machine of the class described, 115 two coöoperative members for punching a hole in the work, and toggle mechanism arranged to move one of said members toward and from the other, said toggle-operated member being movable relatively to its 120 toggle mechanism to feed the work.

40. In a machine of the class described, a setting tool, a punching tool offset laterally

from the setting tool, a combined punching-and-setting tool arranged to co-act alternately with the first two said tools and being movable from one to the other to feed the work, and toggle mechanisms for moving said punching tools toward and from each other, both said punching tools being movable laterally relatively to their respective toggle mechanisms to regulate the length of the feeding steps.

41. In a machine of the class described, a punching tool, a setting tool, a punching-and-setting tool arranged to co-act alternately with said punching tool and said setting tool, regulatable means for operating said punching-and-setting tool to feed the work variable distances and to vary the position of said punching tool relatively to said setting tool, and toggle mechanism for

moving said punching tool toward and from said punching-and-setting tool, said punching tool being movable relatively to said toggle mechanism in response to regulating action of said regulatable means.

42. In a machine of the class described, a punching tool, a setting tool offset laterally therefrom, a punching-and-setting tool arranged to co-act alternately with the first two said tools and to feed the work from one to the other, and a presser-foot carried by said punching tool and arranged to keep the work pressed on said punching-and-setting tool during the feeding motion of the latter.

In testimony whereof I have signed my name to this specification.

PERLEY R. GLASS.
